EXTRACTING APPARATUS

Karl Finsterbusch, Scarsdale, N. Y.

Application March 29, 1940, Serial No. 326,587

1 Claim. (Cl. 196—11)

This invention relates to improvements in methods and apparatus for refining wide boiling range fluid mixtures, more particularly so-called unstabilized or excessively volatile liquids, and for separating or extracting desired constituents or constituent fractions therefrom.

Such mixtures are products of many and varied industrial operations such as, for example, the high pressure cracking of petroleum. Thus, there is commonly obtained, as the overhead product of the main fractionating tower of a high pressure cracking unit, a wide boiling range fluid mixture of gases and vapors including so-called fixed gases, e. g. H₂, CO₁, CO₂ and heavier normally liquid and normally gaseous hydrocarbons. The condensate obtained generally by simple cooling of this overhead product forms the so-called "pressure distillate," an excessively volatile liquid mixture from which, by suitable operations, there may be extracted desired constituents and constituent fractions such as, for example, light and heavy pressure distillate, stabilized as to vapor pressure specification; propane, suitable for use as "bottled gas"; and, other normally gaseous hydrocarbons or mixtures of normally gaseous hydrocarbons utilizable for various purposes.

By a common method of extracting a stabilized pressure distillate from such a mixture concomitant with the recovery of a high percentage of C₃ hydrocarbons, the mixture constituting the charge is cooled and thereby liquefied in part and passed to a gas-liquid separator from which the uncondensed portion, i. e. the "wet" gas containing some of the desired C₃ and heavier hydrocarbons as well as lighter hydrocarbons and fixed gases, passes to a vapor recovery system by means of which the desired C₃ and heavier hydrocarbons are separated from the lighter constituents and are recovered as a product in a liquid state. This is combined with the unstable liquid pressure distillate of the separator for further processing. The combined liquid, however, will nevertheless still contain some excessively volatile hydrocarbons such as C₂ and lighter hydrocarbons unavoidably liquefied in steps of condensation, absorption, etc. but nevertheless undesired in the final product because of their extreme volatility.

Stabilization of such a distillate is a costly procedure and these undesired lighter hydrocarbons in the combined liquid may be, and ordinarily are, eliminated by straight fractionation in a so-called de-ethanizer. Such a de-ethanizer operating at the normal pressure of, for example, from about 550 to about 650 lbs. per square inch

gage, would separate from the combined liquid a substantially C₁—C₂ free liquid as a bottoms product. However, in order to obtain reflux, without the use of expensive refrigeration, when the generally available cooling water is at temperatures of from about 70° F. to 100° F., the gaseous overhead product from the de-ethanizer will normally contain from 15% to 30% of C₃ hydrocarbons, in addition to the undesired lighter constituents, depending upon the relative amounts of C₁ and C₂ hydrocarbons contained in the charge. If high C₃ recovery is desired as an adjunct to stabilization of the charge or as a primary consideration, it would be necessary to incur additional expense and recycle this overhead product to a vapor recovery system for extraction of the C₃ constituents as was done in the case of the separator "wet" gas. The initial cost of such a de-ethanizer unit is relatively high because of the high pressure (550—650 lbs. per square inch) at which the unit must be operated. The unit is also expensive to operate under these conditions because of the high reflux ratios required and the magnitude of the necessary cooling and heating utilities.

An object of my invention, therefore, is to provide a method for separating or extracting desired constituents or constituent fractions from wide boiling range fluid mixtures which will be more economical from the standpoint of operating cost.

Another object of my invention is to provide apparatus for separating or extracting desired constituents or constituent fractions from wide boiling range fluid mixtures which will be more economical from the standpoint of initial cost.

Another object of my invention is to provide a method for separating or removing undesired excessively volatile normally gaseous constituents from a liquid mixture of normally gaseous and normally liquid constituents containing the same without loss, or with a negligible loss, of desired less volatile constituents from the mixture to the end that a high percentage of the less volatile constituents may be recovered in a final product.

Another object of my invention is to provide an improved method and apparatus for refining pressure distillate or similar relatively wide boiling range derivative fractions for the purpose of stabilizing such distillate or derivative fraction through de-methanization, de-ethanization, and the like.

Other and further objects of my invention will appear from the following description, the accompanying drawings, and the appended claim.

In general, the advantageous results obtainable through the use of my invention are predicated upon a recognition of the fact; firstly, that at a given pressure and temperature there is a pronounced spread between the respective vapor-liquid equilibrium constants of the respective light and heavy constituents of a volatile fluid mixture; and secondly, that at a given pressure the ratio to each other of the respective vapor-liquid equilibrium constants of any two constituents increases with decreasing temperature. Thus, for example, for a mixture of normally gaseous and normally liquid hydrocarbons at a given pressure and temperature, the respective vapor-liquid equilibrium constants for the light hydrocarbons, methane and ethane, are higher than those for the heavier hydrocarbons, propane, butane, etc., and the ratios of the respective equilibrium constants of, for example, methane to propane, or ethane to propane, increase as the temperature decreases.

In the accompanying drawings which form part of the instant specification and are to be read in conjunction therewith and in which like numbers refer to like parts throughout the several views:

Fig. 1 is illustrative of one form of apparatus suitable for carrying out the method of my invention.

Fig. 2 is illustrative of another form of apparatus suitable for carrying out the method of my invention.

In carrying out my invention, the fluid mixture from which the desired constituents or constituent fractions are to be extracted is subjected while in a liquid state and starting from a predetermined preferential vaporizing temperature, to a series of venting or flashing operations designed to secure preferential vaporization of certain undesired light constituents or constituent fractions without undue vaporization of the heavier constituents or constituent fractions. Each flashing operation of the series is conducted at a lower pressure than that at which the preceding operation was conducted, each pressure being carefully selected to effect the desired preferential vaporization of undesired constituents or constituent fractions of the mixture at each operation and the attainment of successively lower temperatures of the liquid due to cooling resulting from the latent heat of vaporization. The pressure reduction selected for each venting operation is preferably so chosen that the resulting temperature drop will ensure the maintenance throughout the series of a desired high ratio of the respective equilibrium constants of the undesired to the desired constituents.

The vapors and unvaporized liquid are separated from each other after each venting operation, the liquid being subjected to a succeeding venting operation conducted at a lower pressure. The vented vapors from each operation are preferably subjected to a vapor recovery operation for extraction therefrom and recovery in a liquid state of desired fractions or constituents which may be combined with or recycled to the mixture being processed at a suitable phase of the operation. In some cases it is desirable to discard vented vapors from one or more vents of the series when the content of desired fractions is negligible.

I have found that it is advantageous to carry out the flashing or venting operation by a series of steps from the initial to the final pressure rather than by a single operation from the initial

to the final pressure. By this expedient, a greater amount of the undesired light constituents or fractions and a lesser amount of the desired heavier constituents or fractions are vented from the charge thus appreciably reducing the quantity of desired constituents or fractions to be recovered by the vapor recovery system and measurably reducing the cost of the overall operation.

Referring now more particularly to the accompanying drawings, I have shown in Fig. 1 a system for demethanizing by the use of my invention the overhead product obtained from the main fractionator of a high pressure liquid phase cracking unit concomitant with a high propane recovery in the stabilized distillate product. The overhead product, which product for convenience I shall term the charge, enters the system in a heated gaseous-vaporous state under substantial pressure through the pipe 10 by which it is conducted, after temperature reduction and partial condensation in the coolers 11 and 12, into a gas-liquid separator 13.

The uncondensed "wet" gas portion is conducted from the separator 13 to a vapor recovery unit 14 by a pipe 15, the outlet pressure on the separator 13 being automatically controlled and maintained at a predetermined value by the setting of the pressure controlled valve 16.

The vapor-recovery unit 14 (diagrammatically shown) may include the usual compressors, absorbers, coolers, etc., co-operative in a known manner to extract or effect a separation from the wet gas of those desired constituents which were unavoidably commingled with the undesired constituents of the wet gas portion discharged from the separator 13. Thus, in the demethanization of the charge in the instant operation wherein one of the objects in view is the recovery of as high a proportion as possible of, for example, the C₃ and heavier hydrocarbons in the charge, the vapor recovery unit 14 will be designed to effect a separation of these constituents from the wet gas supplied to it through the pipe 15. These constituents are thereupon conducted in a liquid state from the recovery unit by the pipe 17 into the feed pipe 18 wherein they are commingled with unstabilized pressure distillate flowing therethrough under the pressure in the separator 13.

This combined liquid is conducted by the pipe 18 into the first section 19 of the three-stage demethanizer shown. Cooling of the combined liquid to a preferential vaporizing temperature is effected in its transit through the pipe 18 by means of water cooler 20 and exchanger cooler 21 while the rate of flow is automatically controlled by the setting of a valve 22 actuated in a known manner by a liquid level controlled device 23 responsive to variations in the liquid level in the separator 13.

The cooled combined liquid entering the first flash section 19 of the demethanizer vaporizes in part, due to the lower pressure, with a resultant attendant beneficial temperature reduction of the unvaporized liquid. The vapors and gases evolved by preferential vaporization in the flash section 19, consisting mainly of highly volatile C₁ and C₂ hydrocarbons together with a relatively smaller quantity of less volatile desired C₃ and C₄ hydrocarbons, are conducted therefrom by a pipe 24 into a manifold or header 25 by which they are conducted to the vapor recovery unit 14 for recovery of C₃ and heavier hydrocarbons in a known manner. In some instances it is preferable to treat the vent vapors separately in the

vapor recovery system since they are at a lower pressure than the wet gas.

The pressure within the flash section 18 is maintained at a predetermined value by the setting of a pressure controlled valve 26 and is such that in this, as well as in the succeeding flashing or venting steps, the vapor-liquid equilibrium constant for C₃ hydrocarbons preferably is less than one. Under these conditions, the corresponding equilibrium constant for methane will generally be in the order of eight plus and for the C₃ hydrocarbons in the order of two plus. It is apparent therefore that the vaporizing tendency of the methane and the C₃ hydrocarbons will be very high whereas the C₃ and heavier hydrocarbons will be below their boiling points.

Effective distribution of the unvaporized down-flowing liquid over a considerable area in the flash section 18 may be assisted by means of a distributor 27 of the cone type delivering the liquid over the first of a number of distributing trays or plates 28 such as are well known in the art.

Unvaporized liquid that collects in the lower part of flash section 18 flows through the pipe 29, in quantities regulated by the setting of a valve 30 actuated in a known manner by the liquid level control device 31 in response to the liquid level in flash section 18, into the second flash section 32 of the flash tower wherein due to the lower pressure therein maintained further vaporization of the liquid and consequent temperature reduction is effected. The flash section 32, like flash section 18, is similarly equipped with a distributor 33 and distributing trays 34 and is connected by vapor discharge pipe 35 with the header 25, the pressure within the flash section being automatically maintained by the setting of the pressure controlled valve 36.

Unvaporized liquid that collects in the lower part of the flash section 32 is thereafter subjected to a third but not necessarily final stage of pressure and temperature reduction, being conducted from the section 32 by the pipe 38 into a third section 37 of the demethanizer wherein vaporization and consequent temperature reduction is carried out at a still lower pressure, the flow of liquid through the pipe 38 being controlled in a known manner by the valve 38 actuated by the liquid level control device 39 in response to the liquid level in the flash section 32.

The flash section 37, like flash sections 18 and 32, is similarly provided with a distributor cone 40 and distributing plates 41, and is connected by a gas vapor outlet pipe 42 with the header 25. Pressure controlled valve 43 in the pipe 42 may be set to the desired pressure in the flash section 37.

It will be apparent that the successive pressure reductions in the flash sections 18, 32 and 37 are to be chosen with a view to establishing such temperature levels as will permit achieving the desired beneficial preferential vaporization and elimination of C₂ and lighter hydrocarbons and retention of C₃ and heavier hydrocarbons.

I have found a series of venting or flashing operations to be preferable to a single venting or flashing operation from the initial to the final pressure since a greater amount of the undesired lighter fractions or constituents and a lesser amount of the desired heavier fractions or constituents is vented. Thus, in the instant demethanizing operation, the total of C₃ hydro-

carbons vented by my step flashing system is less than would be vented in a single flash system and the total of C₁ and C₂ hydrocarbons is greater. By my step system, I am able to eliminate through the pipe 25 practically all of the methane and practically 50% of the C₂ hydrocarbons present in the combined liquid feed to the demethanizer, with a venting of about 15% of the C₃ hydrocarbons, about 5% of the C₄ hydrocarbons and practically none of the heavier hydrocarbons. Thus, the total vent gases flowing to the gas recovery system through the pipe 25 will normally contain (on a molal basis) less than 30% of the C₃ hydrocarbons and constituents heavier than C₃ hydrocarbons, and more than 70% of C₂ hydrocarbons and constituents lighter than C₂ hydrocarbons.

The successive evaporations produce a temperature drop in the liquid, the magnitude of which depends upon the concentration of the heavier constituents such as C₃ and heavier hydrocarbons in the feed to the demethanizer. Accordingly, in most cases, it will be found that the final liquid e. g. in the instant operation, that in the third section 37 of the demethanizer, will be from about 10° F. to about 35° F. below the temperature of the combined liquid feed leaving the cooler 20 and will be from about 5° F. to about 30° F. below the temperature of the water normally available as a cooling medium in the charge cooler 11 and in the cooler 20. A low temperature of the combined liquid entering the first section 18 of the demethanizer is more favorable for preferential vaporization. Accordingly, the sub-cooled final liquid is conducted from the third section 37 by a pipe 44 serially through the sub-cooler 21 and charge sub-cooler 12 before being discharged from the system. The flow of this liquid through the pipe 44 is controlled by a suitable pump such as the centrifugal booster pump 45 at a rate regulated by a flow control valve 46 actuated in a known manner by a liquid level control device 47 responsive to variations in the liquid level in the flash section 37.

Residual gas such as the hydrogen, C₁ and C₂ hydrocarbons uncondensed in the vapor recovery unit is released therefrom for other uses through the pipe 47'. The final demethanized liquid discharged from the system through the pipe 44 may be fed to a stabilizer for production of stabilized pressure distillate of desired vapor pressure. In such case, the stabilizer overhead product consisting mainly of C₂, C₃ and C₄ constituents may be condensed, or substantially completely condensed, at pressures below 350 lbs. per square inch gage with cooling water at normal temperatures since this stabilizer overhead product will contain a negligible amount of methane. This overhead product condensate may in turn be fractionated to obtain fractions such as ethane, propane and butane for use as "bottled gas" products or to obtain fractions suitable as charging stock for the manufacture of other products by alkylation or other operations.

If de-ethanization of the final liquid in the pipe 44 is desired, this liquid may be fed to a de-ethanizer unit such as heretofore discussed. Because of the initial de-methanization, operation of the de-ethanizer may be carried out with a lesser quantity of reflux and with less loss of propane to the overhead gaseous product. There is thus obtained a more economical de-ethanization, both from the standpoint of first cost and of operating cost.

Referring now more particularly to Fig. 2, it

will be observed that each flashing operation is combined with an absorption operation for concomitantly extracting from the vaporized constituents certain unavoidably vaporized constituents whose restoration to the unvaporized liquid for recovery as a final product, or as part of a final product, is desired. Thus, in demethanizing a fluid mixture, such as, for example, unstabilized pressure distillate, wherein high propane recovery is one of the objects in view, the body of vaporized constituents resulting from each flashing or venting operation will performe contain some proportion of the constituents such as C_3 and heavier hydrocarbons whose recovery is desired. Restoration of substantially all of these desired constituents to the liquid being processed and their ultimate recovery may be economically and advantageously effected by absorption operations respectively coincident with each flashing operation.

As is depicted in Fig. 2, the wide boiling range charge in gaseous-vaporous state enters the system at an elevated pressure through a pipe 50 by which it is conducted, after temperature reduction in the water cooler 51 and exchanger-cooler 52 productive of substantial condensation, to the gas-liquid separator 53. The uncondensed "wet" gas portion is conducted by a pipe 54 from the separator 53 into the lower part of an absorber 55 while the condensate flows from the separator through a pipe 56 at a rate controlled by a valve 57 actuated in a known manner by a liquid level controlled device 58 responsive to the liquid level in the separator 53.

The wet gas rises upwardly in the absorber 55 through the elements of a series of tray banks 59, 60 and 61, each of which comprises fractionating plates or trays such as are well known to those skilled in the art. The passage of the gas upwardly through the absorber is counter-current to the passage of absorption oil downwardly therein. The absorption oil, preferably having substantially the same boiling range characteristics as the heavy fraction of the charge, enters the absorber in its cool lean state through a pipe 62 and, by absorption, extracts from the wet gas, in its downward progress through the tray banks, mainly those constituents thereof, such as C_3 and heavier hydrocarbons, whose recovery is most desired. Intercoolers 63 and 64 are interposed between the tray banks 59-60 and 60-61 respectively, for removing the heat of absorption from the absorption oil as it passes downwardly through the absorber between the tray banks. The cooling medium for the intercoolers may be water, although if the temperature of the normally available water is too high, a colder medium such as the sub-cooled liquid from the final vent stage may be used.

The unabsorbed dry gas which issues from the absorber through the header pipe 65 is conducted through a pressure controlled valve 66 from the system. The rich oil containing the absorbed constituents which, in the instant case, under the pressure and temperature conditions maintained in the absorber, will consist mainly of C_3 and heavier hydrocarbons, flows into the pipe 58 through a pipe 67 regulated by a valve 68 actuated in a known manner by a liquid level controlled device 69 in response to variations in the liquid level in the absorber 55.

The combined liquid in the pipe 58 is conducted thereby through the water cooler 70 and exchanger-cooler 71 by which its temperature is reduced to a predetermined value, into the first of a series

of demethanizing flash-absorption towers 72, 73 and 74.

These towers are structurally similar. Each comprises a circulating head or channel 75 from which is suspended in each case a tube bundle 76, through which a suitable cooling medium supplied to the channel from a header pipe 77 is caused to circulate and is discharged through an outlet header 78. Thus, the respective channels are supplied with cooling liquid from the header pipe 77 by the pipes 79, 80 and 81 respectively. The liquid after circulating through the respective tube bundles is conducted from the respective channels to the header pipe 78 by the outlet pipes 82, 83 and 84 respectively.

Baffle plates 85 form dams upon which absorption oil collects in pools and flows downwardly around the tubes through annular holes formed between the respective tubes of each bundle and the baffle plates. These baffle plates extend transversely of each of the towers 72, 73 and 74 and of the respective tube bundles at suitably spaced intervals and direct the flow of the rising vapors back and forth across the tubes which are wetted by the absorption oil in its downward flow there-over. The heat of absorption is removed from the absorption oil by indirect heat exchange with the cooling medium as the absorption oil flows in its downward path over the outside of the tubes of the tube bundle in each of the towers.

Absorption oil is supplied in its lean state from a header pipe 62 onto a distribution baffle 85' in each tower by means of the lean oil inlet pipes 86, 87 and 88 respectively and flows downwardly over each tube surface to the oil pool on the baffle plate beneath, annular spaces being provided between each tube and its baffle plate for accomplishing this flow. Gaseous and vaporous constituents which are not absorbed by the lean oil are conducted from the respective towers through the pipes 89, 90 and 91 respectively into the dry gas header pipe 85 and are conducted thereby from the system. Pressure controlled valves 92, 93 and 94 situated in the outlet pipes 89, 90 and 91 respectively maintain the operating pressure of the respective towers 72, 73 and 74 at the desired valve.

Tray banks 84 respectively comprising baffle or fractionating plates well known in the art extend transversely of the respective towers below the charge inlet opening and function to "knock back" or de-entrain liquid particles from volatilized gaseous-vaporous constituents and to disengage the gaseous-vaporous constituents from the descending liquid.

The cooled combined liquid enters the first stage flash-absorption tower 72 through the pipe 58.

The reduced pressure maintained in this tower causes vaporization of a portion of the liquid. The undesired methane and some heavier vaporized constituents rise upwardly in the tortuous path formed by the baffle plates 85 generally counter-current to downflowing cool lean absorption oil. The heat of absorption is dissipated and the absorption oil maintained at a desired operating temperature by indirect heat exchange with the cooling medium circulating through the tube bundle 76. The cooling medium may be water, although I prefer to utilize for this purpose the sub-cooled final liquid obtained as a product of the last stage of the flashing operation. The equilibrium conditions maintained within the tower 72 are preferably such that a relatively minor quantity of C_1 and C_2 hydrocarbons vaporized will be absorbed by the adsorption oil and they will pass

from the tower through the pipe 89 into the dry gas header or residue gas main 65. In the instant operation the equilibrium conditions established in the tower 72 through control of the pressure are preferably such that the vapor-liquid equilibrium constant for C₃ and heavier constituents is preferably less than one. Recovery of these constituents by absorption within the tower is thus easily effected. Moreover, the C₃ and heavier hydrocarbons vaporized are absorbed within the tower at the same pressure as that at which the flashing operation is conducted which is a decided economic advantage.

It is also to be observed that because of the reduced temperature of the volatilized constituents consequent upon the flashing operation and because of the removal of the heat of absorption, the quantity of absorption medium required for recovery of the C₃ and heavier constituents is appreciably reduced.

The rich oil from the upper or absorption section of the tower combines with the separated unvaporized liquid in the lower or flash section of the tower and is conducted to the second stage flash tower 73 by a pipe 88, the rate of flow of the liquid being controlled by a valve 86 actuated in a known manner by a liquid level controlled device 87 responsive to variations in the liquid level in the tower 72.

Flashing of the combined liquid to eliminate more of the methane is again carried out, but at a predetermined lower pressure and consequent lower temperature, in the second stage tower 73, absorption of the vaporized C₃ and heavier constituents being repeated therein and the unabsorbed C₁ and C₂ hydrocarbons being conducted from the tower through the pipe 88 into the dry gas header pipe 65. The combined liquid now at a lower temperature is conducted from the tower 73 to the third stage flash tower 74 through a pipe 97, the rate of flow of the liquid being controlled by a valve 98 actuated by a liquid level controlled device 99 in response to variations in the liquid level in the tower 73.

Final flashing of the combined liquid for elimination of the balance of the methane is carried out at a still lower predetermined pressure and consequent lower temperature in the third stage tower 74, the unabsorbed C₁ and C₂ hydrocarbons being conducted from the tower through the pipe 91 into the dry gas header pipe 65.

The pressure at which the flashing is carried out in each of the flash towers 72, 73 and 74 is preferably so chosen that at the resultant equilibrium temperature preferential vaporization of the undesired constituents will occur. Thus, in the instant operation where demethanization is chiefly sought for the vapor-liquid equilibrium constant established for the C₃ and for the heavier hydrocarbons by the pressure-temperature conditions shall be preferably less than one. Absorption recovery of such C₃ and heavier hydrocarbons as are vaporized under these conditions is more easily effected and preferential vaporization of the lighter undesired hydrocarbons is achieved since their equilibrium constants will be greater than one.

The final liquid which accumulates in the lower portion of the third flash tower 74 is withdrawn therefrom in its sub-cooled state by a centrifugal pump 100 through a pipe 101 and is delivered into the header pipe 77 at a rate controlled by the valve 102 actuated in a known manner by a liquid level controlled device 103 responsive to

variations in the liquid level of the liquid in the third stage tower 74.

The sub-cooled final liquid, i. e. demethanized but as yet commercially unstabilized pressure distillate and rich oil supplied to the header pipe 77 is admirably suited for cooling the absorption oil in the respective demethanizer flash towers by circulation through the respective tube bundles 76, as has previously been described. A portion of this relatively cold liquid upon being discharged into the outlet header pipe 78 after coursing the channels 75 and tube bundles 76 may be utilized further, if desired, to cool absorption oil in the intercoolers 63 and 64. In such case it may be supplied to the intercoolers through the pipe 104 in suitable quantities regulated by the valve 105.

The remainder of the sub-cooled final liquid, or all of the liquid if none be used as a cooling medium in the intercoolers 63 and 64, is conducted by a pipe 106 through the sub-cooler 71 to a diagrammatically depicted stabilizing unit 107. The temperature of the combined liquid flowing through the sub-cooler 71 to the first stage flash demethanizer tower 72 is reduced to a more favorable value by indirect heat exchange with the sub-cooled liquid. A portion of the sub-cooled final liquid may be circulated by the pipe 108 through the exchanger sub-cooler 52 to lower the temperature of the entering charge. Suitable valves 109 and 110 in the pipe 108 and valve 111 in the pipe 106 are operable in an obvious manner to divert the final liquid through the pipe 108 in such quantities as may be deemed necessary. Such portion of sub-cooled final liquid as is caused to circulate through the intercoolers 63 and 64 may be re-combined with the main stream coursing to the distillation unit 107 through the pipe 106, by means of the pipe 112.

The final liquid may be operated on in the distillation unit 107 by suitable well-known methods of distillation, fractionation, rectification, etc., to separate the final liquid into the constituents or constituent fractions desired as products. For example, light and heavy pressure distillate fractions, each stabilized as to vapor pressure specifications, may be recovered in the unit and discharged as products through the pipes 114 and 115 respectively; and, a light liquid hydrocarbon fraction comprising mainly C₃ hydrocarbons, together with such C₄ hydrocarbons as constitute an excess over the quantity of C₄ hydrocarbons required for vapor pressure specifications in the light pressure distillate fraction, and such C₂ hydrocarbons as were not vented with the C₁ hydrocarbons in the demethanizing operation, is discharged from the distillation unit as a product through the pipe 116. This light hydrocarbon fraction may be further fractionated, if desired, to obtain fractions such as ethane, propane and butane for use as "bottled gas" products or to obtain fractions suitable as charging stock for the manufacture of other products by alkylation or other operations.

The stabilized heavy pressure distillate fraction which corresponds generally to the heavy portion of the unstabilized pressure distillate in the separator 53 is suitable for use as an absorption medium in the absorber 61 and in the demethanizer flash-absorption towers 72, 73 and 74. Accordingly, a portion thereof is conducted from the pipe 115 by the pipe 117 into the lean oil header pipe 62 for distribution thereby to the various absorber units as has been described above, the balance of the stabilized heavy pres-

sure distillate being discharged from the system through the pipe 118.

Obviously, however, a separate absorption medium may be used if desired. In some instances, it may be undesirable or not feasible to combine the separate absorption medium in its enriched state with liquid such as that in the separator 53 which would normally be charged to the tower 12 in Fig. 2. In such case, the rich oil from absorber 60 may be processed as in Fig. 2 while the liquid in separator 53 may be flashed in a parallel series of venting operations carried out at successively reduced pressures in a multi-stage vent tower such as that of Fig. 1, the vented vapors from the respective stages being conducted to the respective correspondingly pressured flash absorption towers of Fig. 2 wherein absorption recovery of desired constituents thereof may be carried out under optimum conditions concomitant with series venting and absorption recovery of the rich oil from absorber 60. Again, the liquid charge to the respective flash absorption stages may be supplemented by gases, including recycle gases, from sources outside of the system. Such gases could be introduced to the various absorption stages at suitable phases of the operation for recovery of desired constituents.

In each of the systems described in Figs. 1 and 2, each of the series of venting operations is made up of three stages. Obviously, however, a larger or smaller number of stages may be found desirable. In the actual application of my invention to the recovery from a relatively wide boiling range mixture of normally gaseous and normally liquid hydrocarbons, of a demethanized liquid product containing a high percentage of the C₃ constituents of the mixture, I have found it desirable to use as many as five stages.

In that recovery operation, the mixture in its gaseous-vaporous state was condensed as much as possible at the full operating pressure of 500 lbs. per sq. inch gage, by water cooling. Further cooling and condensation was accomplished by sub-cooling (after the water cooling) with a colder medium. At the high condensing pressure and relatively low temperature, approximately 85% of the C₃ constituents and 95% of the C₄ constituents present in the mixture were condensed. The desirably high percentage of these constituents condensed is attributable in part, at least, to the molal condensing effect of the C₅ constituents and heavier constituents in the mixture. However, for the same reason, relatively large amounts of undesired methane and C₂ constituents were also condensed, the quantity of methane condensed being approximately 30% of the quantity of C₃ constituents condensed, and the quantity of C₂ constituents being approximately 50% of the quantity of C₃ constituents condensed. The total of C₁ and C₂ constituents in such case represents about 80% of the total C₃ constituents, or considering the total of C₃ and C₄ constituents as a desired fraction, the total of C₁ and C₂ constituents formed about 40% of the C₃-C₄ fraction of the condensate, all percentages being on a molal basis.

In order to eliminate economically as much of the methane as possible, without undue loss of C₃ and C₄ constituents, the total liquid condensed was subjected after further cooling to a 5-stage demethanizing operation in a system such as that of Fig. 1. In the first vent stage 19 the pressure on the feed was reduced upon entry from about 500 lbs. per sq. inch gage to approximately 285 lbs. per sq. inch gage with an ac-

companying temperature reduction. Under these circumstances, the relatively small quantity of vapor evolved contained approximately 80% of methane and C₂ constituents and approximately 20% of C₃ and C₄ constituents by composition. Actually the first venting operation eliminated approximately 30% of the methane from the feed and only 3% of the C₃ constituents so that the separation was very favorable. As an accompaniment to this venting operation, the total liquid was chilled by the self-refrigerating effect approximately 5° F. from its initial temperature of about 70° F. The liquid from the first stage was then passed to the second stage 32 wherein the pressure was again reduced with attendant temperature reduction and vaporization of constituents in relative favorable proportions.

The flashing operation was successively repeated in the third, fourth and fifth stages to a final pressure of about 85 lbs. per square inch gage and a correspondingly final temperature of about 43° F. By this series of venting operations approximately 93% of the methane and 50% of the C₂ constituents in the original liquid charged to the first stage were eliminated. The loss of C₃ constituents was about 15% and the loss of C₄ constituents was about 5%.

As compared with the use of a fractionating column, the loss of C₃ constituents was no greater although a fractionating column would have eliminated substantially all C₂ constituents without loss of C₄ constituents. As in the case of a fractionating column, the vent gases in the instant operation were conducted to a vapor recovery unit such as 14 of Fig. 1 where the C₃ and C₄ constituents were recovered.

The sub-cooled liquid from the final stage at 43° F. was used to increase condensation of the separator feed after the water cooling operation described above. The use of this very low temperature liquid for this purpose naturally reduced the loss of C₃ constituents to the gas from the 500 lb. separator. If a fractionating tower were used for elimination of methane and C₂ constituents from the heavier constituents, there would have been no material available for this sub-cooling operation. In consequence, the C₃ loss from the 500 lb. pressure separator would have been much greater. Since the gas from this separator is recycled to the vapor recovery unit 14 for recovery of C₃ constituents, the total C₃ constituents passing to the unit would be approximately the same in each case; i. e., in the case of the fractionating tower, the separator gas plus tower gas would contain approximately the same quantity of C₃ constituents, if not more, than in the case of the vent system where the separator gas and all the vent gases are passed to the vapor recovery unit. Thus, it can readily be seen that the first cost and operating cost of the multistage vent system is a very small portion of the cost of a fractionating unit which would have to be built for 650 lbs. working pressure and include a 30-plate tower, reboiler, reflux condenser, accumulator, pumps, and controllers. Thus, it is apparent that through the use of my invention considerable economies in plant investment and operating cost may be effected.

Thus, it will be observed that I have accomplished the objects of my invention. I have provided a method for eliminating, extracting or separating a constituent, constituents or constituent fractions of relatively high volatility from a mixture thereof with constituents of lower volatility through the use of which marked economies in

operating costs and equipment costs may be effected.

It will be observed that certain features and sub-combinations of my invention are of utility and may be employed without reference to other features and sub-combinations thereof. This is contemplated by and is within the scope of the appended claim. It is further obvious that various changes may be made in details within the scope of the appended claim without departing from the spirit of this invention. It is, therefore, to be understood that this invention is not to be limited to the specific details described.

Having thus described my invention, what I claim is:

Apparatus for obtaining a hydrocarbon liquid of desired volatility from a mixture of gaseous vaporous hydrocarbons comprising in combination; means for cooling the mixture by indirect heat exchange with a colder fluid medium to a

condensing temperature; means forming a series of flash chambers; means for conducting condensate from said cooling means to a first chamber of said series; means for cooling the condensate in transit to said first chamber; means for conducting condensate from a preceding to a succeeding chamber of said series; means for supplying absorption medium to each chamber of said series; cooling means in each chamber; means in each chamber of said series providing a tortuous path of flow for the absorption medium and evaporation products about the cooling means therein; means for conducting non-liquid evaporation products from each said chamber; and, means for conducting condensate from the final chamber of said series to said condensate cooling means for use as the cooling medium therein.

KARL FINSTERBUSCH.
